UNITED STATES PATENT OFFICE.

SUSAN DICKINSON STONE, OF CINCINNATI, OHIO.

DESIGN FOR A PARLOR-GAME DEVICE.

No. 39,443.

Specification for Design.

Patented Aug. 11, 1908.

Application filed April 3, 1908. Serial No. 425,064. Term of patent 7 years.

To all whom it may concern:

Be it known that I, SUSAN DICKINSON STONE, citizen of the United States of America, residing at the city of Cincinnati, in the county of Hamilton and State of Ohio, have invented a new, original, and ornamental Design for a Parlor-Game Device, of which the following is a specification, reference being had to the accompanying drawing, forming part thereof.

My invention consists of a new, original and ornamental design for parlor game device. It is illustrated in the accompanying drawing, which is an elevation showing the design.

The design consists of a pictorial represen-

tation of a brick fireplace (1), a mantel (2) on which appear three candlesticks holding candles. The fireplace is represented as containing andirons and on them burning logs of wood. On the edge of the mantel are represented several pins (3). On the sides of the fireplace are represented a number of stockings (4—4).

I claim:

The ornamental design for a parlor game device, as shown.
